(57) **CLAIM**

The ornamental design for a clock having trapezoidal profile, as shown and described.

DESCRIPTION

FIG. 1 is a front perspective view of a clock having trapezoidal profile according to my new design;

FIG. 2 is a front view of the design of FIG. 1;

FIG. 3 is a rear view of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.

The broken lines depict parts of the clock having trapezoidal profile that form no part of the claimed design.

Conventional contour lines and shading are illustrated for purposes of highlighting the solid-rendering, but form no part of the claimed design.
